CLAIM

The ornamental design for a golf club weight training apparatus, as shown and described.

DESCRIPTION

FIG. 1 is a perspective view of the golf club weight training apparatus according to the design of the present invention. FIG. 2 is an elevation view of the golf club weight training apparatus.

FIG. 3 is a top plan view of the golf club weight training apparatus.

FIG. 4 is a perspective view of a second embodiment of the golf club weight training apparatus; and,

FIG. 5 is an elevation view of a second embodiment of the golf club weight training apparatus.

The sides not shown in the drawing views form no part of the claimed design.
